BURNISHING MAT

Clarence C. Kinker, Manitou Beach, Mich., assignor to Gerity-Michigan Corporation, Adrian, Mich., a corporation of Michigan

Application June 12, 1953, Serial No. 361,244

4 Claims. (Cl. 51—195)

This invention relates to means for burnishing metal articles, and particularly to a mat or other member having a multiplicity of resilient projections thereon for burnishing engagement with the work.

It has heretofore been proposed to provide a polishing or burnishing mat in which the entire body was made from an abrasive impregnated rubber. The abrasive impregnated substance was molded into sheets or pads as well as into a form in which a plurality of work contacting fingers extended from a main body. It has been found that the elasticity of a rubber mass and especially its ability to withstand repeated severe flexings is drastically reduced by the addition of an abrasive. Thus the known abrasive impregnated pads and projections above mentioned are useful only for the finishing of flat surfaces where the bending demands on the elements are not very high.

The primary object of the present invention is the provision of a burnishing means of the class described which has only the surface portion of its resilient burnishing fingers or projections impregnated with an abrasive material, while the main bodies of the fingers or projections are of unimpregnated flexible material. The abrasive used may be of coarse or fine mesh, depending on the grade of burnishing to be performed, thus enabling work-pieces to be successively burnished and polished by series of mats which, in succession, may have the resilient burnishing projections thereof impregnated with first a rough or coarse cutting abrasive, then with a fine cutting abrasive, and finally with a finishing burnishing material.

Further objects and advantages of the invention will be apparent from the following detailed description, and from the accompanying drawings illustrating one embodiment thereof, in which—

Fig. 1 is a plan view of a mat embodying the invention mounted on a carrying member, with parts broken away, and with only a portion of the abrading projections shown, and

Fig. 2 is an enlarged fragmentary edge view thereof, taken on the line 2—2 in Fig. 1, with some of the abrasive impregnated sleeves entirely or partially in central longitudinal section.

Referring to the drawings, 1 designates a mat or surface member that is mounted on a stiff backing or carrying member 2 and having on its outer or exposed surface a multiplicity of rather closely spaced resilient fingers or projections 3 for rubbing or brushing engagement with metal articles to be burnished. In practice, either the articles, the mat, or both, may be relatively moved during burnishing operations.

The projections 3, and also preferably the mat member 1, are composed of resilient material, as for instance soft rubber, whereby the projections have yielding frictional coaction with the articles being burnished or polished.

The projecting fingers 3, in one embodiment that gives good results in practice, are approximately $2\frac{1}{2}$ inches long, circular in cross-section and are tapered lengthwise from a base radius of approximately $1\frac{1}{32}$ of an inch to

an outer end radius of approximately $5\frac{1}{32}$ of an inch and the fingers at their outer ends are spaced approximately $\frac{1}{8}$ inch apart. These measurements are mentioned merely by way of illustration and not as limitations.

5 Mats of the character described have been used in connection with an applied liquid containing a burnishing material in suspension, and particularly where the articles being burnished are submerged in the liquid during the burnishing operation. In such a method, it is necessary to agitate the liquid to maintain the burnishing material in suspension, and while it is desirable to obtain both a rough and fine burnishing, this is not possible in the same bath but necessitates separate operations in different baths or applications of burnishing liquid.

10 The present invention contemplates retaining the resilient character of the projecting fingers themselves, while providing a surface portion thereof, having burnishing engagement with the work, with an abrasive material of the desired grade so that burnishing takes place by frictional coaction of the projections against the work. During such operation, water is applied for cooling purposes, and this may be accomplished either by the submerged method or by playing one or more streams of water against the mats while burnishing. If the submerged 15 method is used, the water may be pumped through a filter and returned to the bath. If the stream method is used, the water may be used over and over by means of a filter and pump.

This use of fingers having impregnated surfaces has 20 an advantage as it allows the successive use on the same work of a series of mats having different grades of impregnated abrasives so that one, for instance, may contain a rough cutting abrasive of about 180 mesh, the next a medium coarse abrasive of, for example, 240 mesh, then an abrasive of, for example 325 mesh, and finally an abrasive suitable for the finishing operation, such as an air borne or flour size abrasive mesh.

We have found that rubber impregnated with an abrasive or other dissimilar hard materials is very brittle, 25 the same as a rubber ink or pencil eraser, and thus entirely unsuited for use where great flexibility is a requirement because of its inherent inability to withstand rugged service and continuous flexing as is found where the work-pieces have domed or ridged or discontinuous surfaces that must be burnished.

The present invention is based on the provision of 30 resilient fingers of mats of this character having only the working portions thereof provided with an abrasive impregnated coating or of a covering member impregnated with a suitable abrasive. This leaves the body of the burnishing finger, or at least the major portion thereof, composed of strong, durable, resilient stock, whereby breakage and deterioration in use are reduced to a minimum.

35 In practice, the object of the present invention is preferably accomplished by providing an abrasive impregnated sleeve or nipple 5 of soft rubber or the like, and fitting one of these sleeves over the working end portion of each of the abrading fingers 3. The sleeve is preferably 40 fixed in place by cementing or otherwise in such a manner that it can be removed only by immersion in a suitable solvent. These sleeves preferably stop short of the base of the fingers so as to enable full advantage to be taken of the strength and resilience of the non-impregnated rubber stock at the base portions of the fingers where it is most needed. In event the abrasive impregnated portion of a finger is in the form of a sleeve or nipple that is fitted down over the finger, it is provided at its outer 45 or blind end with a perforation 6 through which the entrapped air may escape. As wear in use occurs, the worn down sleeve portion may be removed from the flexible

finger 3 by applying a solvent and a new sleeve portion then substituted therefor on the finger.

I wish it understood that my invention is not limited to any specific construction, arrangement or form of the parts, as it is capable of numerous modifications and changes without departing from the spirit of the claims.

I claim:

1. In a burnishing mat or the like having a plurality of resilient rubber-like abrading fingers, a sleeve of pliant plastic material impregnated with abrasive material, fitted over and covering the burnishing end portion of each finger, and means to releasably engage said impregnated sleeve and finger.

2. In a burnishing mat or the like having a base portion and a plurality of laterally spaced resilient rubber-like abrading fingers projecting outwardly from a surface of said base portion, the provision of a sleeve of pliant plastic material impregnated with an abrasive material fitted over and covering the burnishing end portion of each finger in spaced relation to the base portion thereof, whereby each finger has a neck portion at its inner end the flexing of which is not interfered with by its sleeve.

3. In a burnishing mat or the like having a base portion and a plurality of laterally spaced resilient rubber-like abrading fingers projecting outwardly from a surface of said base portion, the provision of a sleeve of pliant plastic material impregnated with an abrasive material fitted over and covering the burnishing end portion of each finger in spaced relation to the base portion thereof, whereby each finger has a neck portion at its inner end

the flexing of which is not interfered with by its sleeve, each sleeve being releasably attached to its finger to permit replacement.

4. In a burnishing mat or the like having a base portion and a plurality of laterally spaced resilient rubber-like fingers projecting outwardly therefrom, said fingers each tapering so as to be reduced in size from near its inner end to its outer end, the provision of a sleeve of pliant plastic material impregnated with an abrasive fitted over the outer tapered end portion of each finger and terminating short of said base to provide a neck portion the resiliency of which is not interfered with by the respective sleeve portion, said sleeve being releasably secured to the fingers for replacement.
